UNITED STATES PATENT OFFICE.

WILLIAM I. F. HARDEN, OF WASHINGTON, DISTRICT OF COLUMBIA.

RAILWAY-TIE.

No. 833,048.

Specification of Letters Patent.

Patented Oct. 9, 1906.

Application filed March 27, 1906. Serial No. 308,313.

To all whom it may concern:

Be it known that I, WILLIAM I. F. HARDEN, a citizen of the United States, residing at Washington, in the District of Columbia, 5 have invented certain new and useful Improvements in Railway-Ties; and I do hereby declare the following to be a full, clear, and exact description of the invention, such as will enable others skilled in the art to which it appertains to make and use the same.

My invention relates to the construction of railway-ties and means for securing rails thereto.

It has for its object to provide a metal tie 15 which is simple of construction, cheap of manufacture, and durable.

This invention constitutes an improvement on the ties shown, described, and claimed in my Patents No. 802,450, dated 20 October 24, 1905, and No. 807,377, dated December 12, 1905, and in my pending application, filed December 15, 1905; Serial No. 291,937.

The invention consists of a steel or iron 25 hollow tie made, preferably, angular in cross-section, with its top closed, its bottom open, and provided with flanges or wings extending from its bottom edges, said flanges being preferably corrugated to better hold the ballast.

The invention also consists of means, such as hereinafter described, for securing the rails to the ties.

35 In the accompanying drawings, illustrating the preferred embodiment of my invention, Figure 1 is a plan view of a section of track showing three ties constructed in accordance with my invention, two of said ties having 40 broad meeting flanges, while the third tie is provided with narrower flanges. This view shows the track before the ballasting is put on. Fig. 2 is a longitudinal vertical sectional view of a section of track, corresponding to that 45 shown in Fig. 1, but with the ballasting in place. Fig. 3 is an under plan view of one end of the right-hand tie in Figs. 1 and 2. Fig. 4 is a vertical sectional view of one end of said tie, taken on the line $z-z$ of Fig. 1. 50 Fig. 5 is a side elevation of a tie provided with wear-plates below the rails and having slots in the vertical side portions, for the purposes hereinafter explained. Fig. 6 is a plan view of one end of the tie shown in Fig. 5, with the rail removed from the clamping devices. Fig. 7 is a perspective view of the

wear-plate shown in Figs. 5 and 6. Fig. 8 is a plan view of one end of a tie fitted with a modified form of wear-plate, the tread of the rail being broken away. Fig. 9 is a vertical 60 sectional view, taken longitudinally, of one end of a tie provided with said modified form of wear-plate, the rail being removed. Fig. 10 is a plan view of the end of a tie equipped with another modified form of wear-plate. Fig. 11 is a cross-sectional view of two ties 65 which have flat flanges with turned-up edges bolted together to form a continuous metal road-bed. Fig. 12 is a cross-sectional view of a tie formed with flanges of thinner metal 70 than the body of the tie, and Fig. 13 is a similar sectional view of a tie formed with corrugated flanges or wings of thinner metal than the body of the tie secured to narrow extending flanges on said body portion. 75

Referring more particularly to the drawings, and first to Figs. 1, 2, 3, and 4, each tie comprises a horizontal top 1, vertical sides 2, and extending horizontal flanges or wings 3. Said flanges or wings are preferably corrugated, as shown in the above-mentioned figures; but they may be flat, as shown in Figs. 11 and 12. The width of the flanges may be varied to suit conditions. They may be extended so as to lap over each other, as shown 85 in the two left-hand ties in Figs. 1 and 2, or they may be made narrower, as shown in the right-hand tie in said figures. When the flanges are extended so as to lap one another, the ties form a continuous metallic road-bed. 90 As shown in Fig. 11, the flanges are flat with turned-up edges 4, secured together by rivets or bolts 5. In Fig. 12 the flanges are made of plates 6, much thinner and lighter than the body of the tie. Said plates 6 are flanged at 7 95 and secured to the vertical sides of the tie by means of rivets 8. In Fig. 13 is shown a tie with corrugated flange-plates 9, riveted to narrow flanges 10 on the body of the tie. The flanges or wings, however formed, provide 100 broad bases to the ties, which are held firmly in place by the ballasting shown at 11 in Fig. 2. Each of the ties shown in Figs. 1 to 4, inclusive, has a lip 12, cut from the top thereof near each end, said lip being bent upwardly 105 at an angle with the surface of the top for the purpose of engaging one side of the foot of a rail. Both lips on the same tie extend in the same direction, whereby the tie may be substituted for others in a track already laid, 110 both lips engaging their respective rails at the same time as the tie is slid into place from

either side of the track. It will be noted that I have overcome the defect in some old forms of ties which have the lips bent toward each other, thereby rendering them incapable 5 of being used as substitute ties. The side of the foot of the rail not engaged by the lip cut from the top of the tie is secured by a forged lug-bolt 13, screw-threaded and extending into a socket formed in the top of the tie.

10 The socket also extends through a reinforcing-plate 14, secured to the under side of the top of the tie by means of bolts 15, inserted from below and fastened by nuts 16 on their outer ends. The bolt is made long enough to project through the reinforcing-plate. In case 15 the head should be broken off of the bolt the reinforcing-plate may be removed, the portion of the bolt remaining in said plate removed with a pair of pliers, the plate secured 20 in place again, and a new bolt used.

Referring particularly to Figs. 5, 6, and 7 of the drawings, I have there shown a wear-plate 17 inserted between the tie and the rail. Said wear-plate may be made of sheet metal 25 with a lip 18 turned over at one end to engage one side of the foot of the rail and a recess 19, cut from the other end, to fit around the lip 12, cut from the top of the tie. The edges of the wear-plate are turned down, as 30 at 20, and preferably extend a little way beyond the lip on said plate, where they are provided with holes 20^a (see Fig. 7) for the securing-bolt 21, whereby and by means of the lip on the tie said wear-plate is held in 35 position.

Fig. 8 and 9 illustrate another form of wear-plate 22, which is used on a tie from which no lips are cut. This wear-plate may also be made of sheet metal having one end 40 23 turned over, but standing up to engage one side of the foot of the rail, and the other end 24 turned over flat and provided with a screw-threaded socket to receive a lug-bolt of similar construction as that previously 45 described. The wear-plate is itself secured to the tie by means of bolts 25 at each end thereof, said bolts being introduced from below and fitted with nuts on their outer ends.

Fig. 10 shows still another modified form 50 of wear-plate 26, both ends of which are bent over flat upon it, and a screw-threaded lug-bolt is used on each side for securing the rail. The edge of the flat turned-over ends of this wear-plate, as well as of that shown in Figs. 8 55 and 9, are arranged to abut against the edge of the foot of the rail.

In Figs. 4, 5, and 9 I have shown slots or openings 27 in the sides of the tie near each end. These openings are provided for gripping 60 the ties when handling them—as, for instance, in loading and unloading them and in putting them in place on the track. These openings may also be fitted with suitable insulation and carry electric cables for supplying 65 electric railways, &c. When cables are

laid in this way, they are covered by the ballasting on the road-bed, and the building of a separate conduit is unnecessary. The flanges of the tie may be provided with perforations 28, as shown in Fig. 8, whereby it may be 70 bolted to bridges, &c.

I claim—

1. A metallic railway-tie having corrugated extending base flanges or wings.

2. A metallic railway-tie having a closed 75 top, upright sides and corrugated extending flanges or wings.

3. A metallic railway-tie having base flanges or wings, each extending to the adjacent flange on the next tie.

4. A metallic railway-tie having base flanges or wings, each extending to, and having means of engagement with the adjacent flange on the next tie.

5. A metallic railway-tie having a closed 85 top, upright sides and flanges or wings, each extending to the adjacent flange on the next tie.

6. A metallic railway-tie having a closed top, upright sides and flanges or wings, each 95 extending to, and having means of engagement with the adjacent flange on the next tie.

7. A metallic railway-tie having corrugated base flanges or wings, each extending to, and interlapping with the adjacent flange 95 on the next tie.

8. A metallic railway-tie having a closed top, upright sides and corrugated base flanges or wings, each extending to, and interlapping with the adjacent flange on the next tie.

9. A metallic railway-tie having base flanges or wings, each extending to meet the adjacent flange on the next tie, the edges of said flanges turned up and adapted to be secured to those of adjacent ties.

10. A metallic railway-tie having base flanges or wings made of thinner metal than the body of the tie.

11. A metallic railway-tie having upright side pieces provided with openings at each 110 end on opposite sides thereof and a closed top portion at each end.

12. A metallic railway-tie having a horizontal top and upright sides, said top having two lips cut therefrom extending in the same 115 direction, one for engaging one side of each rail, a reinforcing-plate removably secured to the under surface of said top near each lip and lug-bolts, one engaging a socket extending through the top and each reinforcing-plate, the heads of said bolts adapted to secure the other sides of said rails.

13. The combination with a metallic railway-tie having a horizontal top and upright sides, said top having a lip cut therefrom for engaging one side of a rail, of a wear-plate having one end turned over to engage the other side of said rail, the other end of said plate being recessed to fit around said lip, and means to secure said plate to the tie. 130

14. The combination with a metallic railway-tie having a horizontal top and upright sides, said top having a lip cut therefrom for engaging one side of a rail, of a wear-plate having one end turned over to engage the other side of said rail, the edges of said plate being turned down over the sides of the tie and provided with bolt-holes, and a securing-bolt passing through said holes and the tie. 35
15. The combination with a metallic railway-tie having a horizontal top and upright sides, said top having a lip cut therefrom for engaging one side of a rail, of a wear-plate having one end turned over to engage the other side of said rail, the other end of said plate being recessed to fit around said lip, the edges of said plate being turned down over the sides of the tie and provided with bolt-holes, and a securing-bolt passing through 40 said holes and the tie. 45
16. The combination with a metallic railway-tie having a horizontal top and upright sides, said top having two lips cut therefrom and extending in the same direction, each of 50 said lips adapted to engage one side of a rail, of two wear-plates, one adapted to fit under each rail, each wear-plate having one end turned over to engage the other side of the rail above it, the other end of said plate being recessed to fit around said lip, and means to secure said wear-plates to the tie. 55
17. The combination, with a railway-tie, of a wear-plate secured to said tie, one end of 60
- said plate turned over to engage one side of a rail, and a screw-threaded lug-bolt for securing the other side of the rail, the head of said bolt engaging the foot of the rail, and its shank extending through the wear-plate and the top of the tie. 65
18. The combination, with a railway-tie, of a wear-plate secured to said tie, one end of said plate turned over to engage one side of a rail and the other end bent flat thereon and abutting against the other side of the rail, and a screw-threaded lug-bolt for securing the last 70 mentioned side of the rail, the head of said bolt engaged with the foot of the rail and its shank extended through the two thicknesses of the wear-plate and also through the top of the tie. 75
19. The combination, with a railway-tie, of a wear-plate secured to said tie, the ends of said plate bent flat thereon and abutting against the opposite edges of a rail, and screw-threaded lug-bolts to secure the opposite sides of said rail, the head of each bolt engaged with the foot of the rail and its shank extended through the two thicknesses of the wear-plate and also through the top of the tie. 80

In testimony whereof I affix my signature in presence of two witnesses.

W. I. F. HARDEN.
